Primary Examiner—Melody N. Brown
Attorney, Agent, or Firm—Oppenheimer Wolff & Donnelly LLP[57] **CLAIM**

The ornamental design for a truck body, as shown and described.

DESCRIPTION

FIG. 1 is a rear perspective view of a truck body showing our new design;

FIG. 2 is a front perspective view thereof;

FIG. 3 is a side view thereof, opposite the side shown in FIGS. 1 and 2;

FIG. 4 is an end view thereof;

FIG. 5 is a top plan view of the new design of the truck body of FIGS. 1 to 4;

FIG. 6 is a rear perspective view of a second embodiment of a truck body showing our new design;

FIG. 7 is a top plan view of the new design of the truck body of FIG. 6; and,

FIG. 8 is a rear view of the truck body of FIG. 6.

The broken lines shown in all drawing views are for illustrative purposes only and form no part of the claimed design.
